CANDLEHOLDER

Russell J. Bibeau, White Bear Lake, Minn.

Application March 2, 1953, Serial No. 23,858

Term of patent 3½ years

(Cl. D48—2)

To all whom it may concern:

Be it known that I, Russell J. Bibeau, a citizen of the United States of America, residing at White Bear Lake, Minnesota, have invented a new, original, and ornamental Design for a Candleholder, of which the following is a specification, reference being made to the accompanying drawing, forming a part hereof, and in which:

Fig. 1 is a top plan view of a candleholder showing my new design;

Fig. 2 is a side elevational view thereof; and

Fig. 3 is a perspective view.

I claim:

The ornamental design for a candleholder, substantially as shown.
